(57) **CLAIM**

The ornamental design for a children tricycle, as shown and described.

DESCRIPTION

FIG. 1 is a bottom-front-left side perspective view of a children tricycle embodying my new design;

FIG. 2 is a top-rear-right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an enlarged and partial perspective view of area 9 in FIG. 2.

The broken lines shown in the drawings depict portions of the children tricycle that form no part of the claimed design. The dot-dash lines in FIGS. 2 and 9 are provided for annotative purposes to graphically indicate the areas of enlargement. The dot-dash lines do not represent actual structure and do not form part of the claimed design.
